UNITED STATES PATENT OFFICE.

WILLIAM O. BOWMAN, OF OAKLAND, CALIFORNIA.

ADJUSTABLE IRONING-BOARD.

SPECIFICATION forming part of Letters Patent No. 771,856, dated October 11, 1904.

Application filed May 8, 1902, Serial No. 106,465. (No model.)

To all whom it may concern:

Be it known that I, WILLIAM O. BOWMAN, a citizen of the United States, residing at 1008½ Seventh street, Oakland, in the county of Alameda and State of California, have invented certain new and useful Improvements in Adjustable Ironing-Boards; and I do hereby declare the following to be a full, clear, and exact description of said invention, such as will 10 enable others skilled in the art to which it most nearly appertains to make, use, and practice the same.

This invention relates to improvements in auxiliary tables, and particularly to ironing-tables.

The object sought to be accomplished is to provide an extension adjustable to varying heights of tables or any overhanging shelf edge; further, to so construct and apply the 20 extension that any load placed thereon shall be supported almost entirely by the said extension.

The invention comprises a leg having an adjustable lug fixed to the upper side of the 25 head and a fixed lug on the opposite side in contraposition to the adjustable lug and adapted to engage the edge of a table from which the leg inclines downwardly, a board having its head centrally and longitudinally recessed 30 to pass the head of the leg and extend under the edge of the table, a cleat fixed across the under side of the board in juxtaposition to the inner extreme end of the recess adapted to engage the above-mentioned adjustable lug, 35 and adjustable stops fixed to the top of the board abutting the edge of the table.

In the drawings, Figure 1 represents a side elevation of an ironing-board constructed in accordance with this invention as applied to 40 the edge of a table. Fig. 2 is a plan view from above of the same. Fig. 3 is a detail plan of the under side of the ironing-board, showing the recess and the cleat. Fig. 4 is a detail in side elevation of the head of the leg, 45 showing the form and position of the lugs and the manner of affixing same. Fig. 5 is a detail in plan of the same.

In the description with reference to the accompanying drawings similar letters of ref-

erence refer to similar parts throughout the 50 several views.

In construction the invention consists of the leg A, having the fixed lug A' attached to the under side of the head by the bolt A², extending through the head. The leg A under ordinary conditions sets at an incline of about forty-five degrees from the edge of the table X, the upper side of which is engaged by the lug A'. The adjustable lug A³ comprises the flat extended portion in which the slot A⁴ is 60 cut, through which the bolt A² extends, and the lower upturned end forming the notch or recess A⁵, the lug being fixed in the desired position by the wing-nut A⁶, threaded onto the bolt.

The ironing-board B may be of any desired shape to suit its function. Whether it be used as an ironing-board or as an auxiliary table is immaterial. The head of the board B is recessed centrally and longitudinally, B', to pass 70 the head of the leg A and extend under the edge of the table X. The cleat B² is fixed across the under side of the board in juxtaposition to the inner extreme end of the recess B'. The body of the cleat B² is V-shaped in cross-section to fit the notch A⁵, formed in the adjustable lug, the extremities being flattened 75 and extended to act as a transverse brace for the board B. The stops C are adjustably screwed to the top of the board B, abutting 80 the edge of the table X, against which they impinge to prevent lateral action of the board.

In operation the leg is leaned against the edge of the table, shelf, or other overhanging edge to which it is to be applied, the lug A' 85 resting on the top of the table. The board B is placed in position, the recess B' passing the head of the leg, the cleat B² engaging the recess A⁵ in the adjustable lug, and the edge of the board passing under the edge of 90 the table. The lug A³ is raised or lowered on the leg until the surface of the board is level, a very slight adjustment of the lug materially altering the plane of the board by reason of its location being the fulcrum of the board 95 and the leg. When the board has been leveled, the stops C are set against the edge of the table X to prevent lateral action of the

board. When all the parts have been so adjusted, the board may be set up and taken down with regard to this particular height of table without altering the various adjustments. 5 When it is desired to apply it to a table of different height, it will be necessary to alter the adjustments, as before described, to suit the circumstances.

The leg A may be made extensible without 10 altering the spirit of the invention.

By the system of leverage embodied in this invention all downward strains applied to the board B beyond the fulcrum A⁵ (away from the head) are taken up by the leg A. In this 15 manner the lifting action of the board offsets the downward strains exerted by the head of the leg resting on the table X. In this manner a table totally inadequate for supporting a heavy weight will, however, serve the auxiliary board in supporting it.

Having thus described this invention, what is claimed, and desired to be secured by Letters Patent, is—

1. In an ironing-table, a leg having an adjustable piece on its upper side for supporting the board, a stationary piece on its under side adapted to rest on top of an ordinary table, and a bolt adapted to hold the upper piece in its adjusted position, the same bolt holding the lower piece stationary. 25

2. In an ironing-table, a leg having a stationary lug on its under side adapted to rest on the top of an ordinary table, an adjustable lug on the upper side of said leg, a bolt for adjustably holding the upper lug on the leg, 35 said bolt holding the lower lug stationary, a board centrally slotted for a part of its length, and a cleat on the under side of said board at the inner end of the slot and adapted to rest on said adjustable lug. 30

In testimony whereof I have hereunto set my hand this 29th day of March, 1902.

WILLIAM O. BOWMAN.
